CLAIM

The ornamental design for a belt strap and hook fastener strap for protective eyewear case, as shown and described.

DESCRIPTION

FIG. 1 is a perspective view of the belt strap and hook fastener strap for protective eyewear case;

FIG. 2 is a front view thereof;

FIG. 3 is a right side view thereof, the left side being a mirror image thereof;

FIG. 4 is a back view thereof;

FIG. 5 is a top view thereof;

FIG. 6 is a bottom view thereof;

FIG. 7 is a perspective view on a reduced scale of an eyewear case attached thereto, the dashed line showing of the eyewear case is for illustrative purposes only and forms no part of the claimed design; and,

FIG. 8 is a left side view on a reduced scale with an eyewear case attached thereto, the dashed line showing of the eyewear case is for illustrative purposes only and forms no part of the claimed design.
